UNITED STATES PATENT OFFICE

165,861

MERCHANDISE RECEPTACLE

Richard E. Paige, New York, N. Y.

Application December 31, 1949, Serial No. 6,939

Term of patent 14 years

(Cl. D58—12)

To all whom it may concern:

Be it known that I, Richard E. Paige, a citizen of the United States, residing in the city, county, and State of New York, have invented a new, original, and ornamental Design for a Merchandise Receptacle, of which the following is a specification, reference being had to the accompanying drawings, forming part thereof.

I claim:

The ornamental design for a merchandise receptacle, as shown.

RICHARD E. PAIGE.
